REFRIGERATING APPARATUS

Thomas S. Wetter, New York, N. Y.

Application May 14, 1937, Serial No. 142,565

6 Claims. (Cl. 62—3)

This invention relates to improvements in refrigerating apparatus, and has particular relation to improved control mechanism for refrigerating apparatus.

5 It is an object of the invention to provide improved refrigerating apparatus whereby a more uniform temperature may be maintained in the space or object to be refrigerated.

In the ordinary automatic refrigerating system, 10 control mechanism usually consists of a pressure control operated by a variation in the evaporator pressure or a thermostat operated by a variation in temperature of the space or product to be cooled. With either type of mechanism there is 15 usually a temperature variation of several degrees due to a great extent to the fact that during the period when the refrigerating machine is shut down the evaporation of the refrigerant continues and builds up the pressure in the evaporator to a 20 point above the normal operating pressure and before refrigeration is obtained it is necessary for the refrigerating apparatus to reduce the evaporator pressure to the normal operating pressure.

It is a particular object of the invention to overcome the undesirable relatively large fluctuation 25 in temperature resulting from refrigerating apparatus of the type heretofore employed and to provide improved control mechanism for maintaining a more uniform temperature in the space 30 or object to be refrigerated.

For a fuller understanding of the invention, reference should be had to the accompanying drawing showing a diagrammatic illustration of one form of refrigerating apparatus embodying 35 my invention.

My invention may be used in association with any type of conventional refrigerating apparatus having a compressor, condenser and evaporator. In the accompanying drawing one form of refrigerating apparatus is shown consisting of compressor 1 operated by an electric motor 2 and having inlet and outlet ducts 3 and 4, respectively. The inlet duct 3 is provided with a valve 5 which opens on the intake stroke of the compressor and 45 closes on the compression stroke, while the outlet duct 4 is provided with a similar but oppositely operating valve 6 which closes on the intake stroke and opens on the compression stroke. The refrigerating fluid accordingly is drawn into the 50 compressor through duct 3 and forced outwardly through duct 4, whence it is fed to the condenser 7 where the heat is extracted from the fluid. From the condenser 7 the refrigerant passes through pipe 8, through expansion valve 9, into evaporator 10 which is of the coil type.

The expansion valve 9 is of the conventional thermostatically controlled type, being connected by a tube or duct 11 to a thermobulb or jacket 12 surrounding outlet pipe 14 which leads from the evaporator coil 10.

5 The apparatus heretofore described is one of the conventional types of refrigerating apparatus and is merely intended as illustrative of the type of apparatus to which my invention may be applied. In association with the refrigerating apparatus, I employ improved control mechanism which effectively prevents too great a fluctuation in the temperature of the space to be refrigerated. In carrying out my invention I provide means having relatively great volumetric capacity be- 15 tween the outlet of the evaporator and the compressor, thereby forming a space of reduced pressure which can immediately reduce the pressure in the evaporator to the desired operating pressure when the refrigerating machine is set into 20 operation.

Thus the pipe 14 is connected to a suction tank 15 which in turn has connection through pipe 16 with the intake 3 of the compressor. The tank 15 is of relatively large capacity relative to the 25 capacity of the evaporator 10 and is preferably maintained at a pressure lower than the desired operating pressure of the evaporator. In this way when the refrigerating apparatus is set into operation the tank 15 can immediately reduce the 30 pressure of the evaporator without the pressure in the tank being greatly affected, and accordingly the operating time of the refrigerating apparatus is not wasted by having the compressor first reduce the pressure of the evaporator to normal 35 operating pressure.

So that the pressure in the line 14 may be readily observed, I preferably place a gauge at some convenient place in the line, as indicated at 40.

45 In the line 14 between the evaporator 10 and the tank 15 I provide a pressure regulating valve 18 of the suction pressure type and thermostatically controlled valve 19 which automatically opens when the temperature of the space or object to be refrigerated rises to a predetermined point. The pressure regulating valve 18 is of the well known suction pressure or back pressure type and is intended to maintain the pressure in the evaporator at the desired operating pressure even though the pressure in the tank 15 should be considerably below that level. The pressure at which the valve 18 is set depends upon the refrigerant employed and also upon the temperature which it is desired to maintain in the 50 55

space to be refrigerated and also the expected or average heat infiltration in that space. Thus, for example, where Freon is employed as the refrigerant, and where it is desired to maintain the temperature of a space at 58° F., and it is determined from the average heat loss that the operating temperature of the evaporator 10 should be approximately 48° F., the pressure regulating valve 18 is adjusted so as to maintain a gauge pressure in the line 14 of approximately 45 lbs.

The thermostatically controlled valve 19 is operated by a solenoid 20 which is connected by leads 21 and 22 to one side of a source of current supply and by lead 23 to contact 24 of thermostatic switch 25. The switch 25 is provided with a thermostatically operated movable contact 26 having an elongated head 27 and which has connection through lead 28 to the other side of the source of current supply. The valve 19 is normally closed so as to shut off the connection between the evaporator 10 and suction tank 15, but when a predetermined temperature is reached the contact 26 automatically engages contact 24 closing the circuit of solenoid 20 and opening the valve 19. Since as previously stated the pressure tank 15 is maintained at a level below the desired operating pressure of the evaporator 10 the pressure of the evaporator will be immediately reduced to the desired amount when the valve 19 is open. Pressure regulator valve 18 prevents a reduction of the pressure in the evaporator below the desired level.

At times the heat infiltration is greater than expected, with the result that the operation of the refrigerating machine at the pressure determined by the regulating valve 18 is not sufficient to overcome the heat infiltration and the temperature will continue to rise. To meet this contingency I provide a by-pass in the form of pipe 30 connected at one end to the pipe 14 between the evaporator and the regulating valve 18 and at its other end to the pipe 16. The pipe 30 is controlled by a thermostatic valve 31 operated by solenoid 32. The solenoid 32 is connected by leads 33 and 22 to one side of the source of current supply and by lead 34 to fixed contact 35 of the thermostatically operated switch 25. The contact 35 is positioned so as to be engaged by contact 26 upon the continued rise in temperature in the space or object to be refrigerated above the temperature at which the contact 24 is operated.

The pipe 30 has no pressure regulating valve, such as the valve 18 disposed therein, and accordingly when solenoid 32 causes valve 31 to open, the pressure in pipe 14 and in the evaporator 10 is reduced below the pressure which is permitted by the pressure regulating valve 18 upon the opening of valve 19. The result is that upon the opening of valve 31 the pressure and temperature of the refrigerant in the evaporator and accordingly the temperature of the evaporator decreases, causing a more rapid cooling of the space which should be sufficient to overcome the additional heat infiltration.

Tank 15 is maintained at the desired reduced pressure by means of compressor 1. When the pressure in the tank 15 rises above the desired amount the compressor is caused to operate to reduce the pressure. This may be accomplished by means of a conventional type of diaphragm or similar pressure operated switch as shown at 36 which is controlled and operated by the pressure in tank 15. The switch is connected by lead 37 to one side of a source of current supply and by lead 38 to the compressor operating motor

2. The compressor operating motor is also connected by lead 39 to the opposite side of the source of current supply. When Freon is employed as the refrigerant and it is desired to maintain the evaporator coils at a temperature of approximately 48° F. and the pressure is set at 45 lbs. gauge pressure, I have found that satisfactory results are obtained by maintaining the pressure in tank 15 at between 10 and 25 lbs. gauge pressure. Thus the switch 36 may be adjusted so as to cause the compressor motor 2 to operate when the pressure rises to 25 lbs. and to shut the motor off after the pressure has been reduced to 10 lbs.

As an illustration of the manner in which my apparatus may be operated, let us assume that Freon is employed as the refrigerant and that it is desired to maintain the space refrigerated at approximately 58° F. Let it be further assumed that the heat infiltration and other factors are such that the evaporator coil 10 should have an operating temperature of approximately 48° F. in order to maintain the room at the desired temperature. The thermostatic switch 25 is then adjusted so as to cause the closing of contact 24 at 58 $\frac{1}{2}$ ° and the closing of contact 35 at 58 $\frac{1}{2}$ °. If greater temperature fluctuations are permissible the thermostatic switch may be adjusted so as to cause the closing of the contacts at higher temperatures such as 58 $\frac{1}{2}$ ° and 59°. The settings of the switch will of course depend upon the degree of uniformity of temperature which it is desired to maintain. The pressure regulating valve 18 is adjusted so as to maintain a gauge pressure of 45 lbs. in the line 14 and evaporator 10, and the switch 36 is adjusted so that the gauge pressure of tank 15 will be maintained between 10 and 25 lbs. as previously described.

When the device is thus adjusted and the temperature in the space to be refrigerated rises to 58 $\frac{1}{2}$ ° contact 24 will be closed causing solenoid 20 to open valve 19. Since the capacity of tank 15 is large relative to the capacity of evaporator 10 and since the pressure is maintained at between 10 and 25 lbs., the opening of valve 19 results in an immediate reduction of the gauge pressure of evaporator 10 to 45 lbs., thereby effectively and immediately eliminating any fluid pressure that is built up in the evaporator due to the evaporation of the refrigerant while the refrigerating apparatus was inoperative. Accordingly there is no delay occasioned by a slow reduction of the pressure in the evaporator by the compressor and the apparatus may operate almost immediately to refrigerate the space after the opening of valve 19.

Since the apparatus has been adjusted or regulated so that the temperature of evaporator 10 when operating at 45 lbs. gauge pressure is sufficient to overcome the normal heat infiltration, the opening of valve 19 is usually sufficient to cause the gradual reduction in temperature in the space to be refrigerated. However, under certain conditions the heat infiltration may be greater than usual, with the result that evaporator 10 may not be able to overcome it when operating at 45 lbs. gauge pressure, with the result that the temperature in the space to be refrigerated continues to rise until contact 35 is closed, causing solenoid 32 to open valve 31, thereby by-passing pressure regulator 18. The result of this is to reduce the pressure in the evaporator below that permitted by pressure regulating valve 18, the pressure in the evaporator being reduced to 35 lbs. or less depending upon the pressure existing in tank 15 at that time.

The reduction in the pressure in the evaporator causes a greater cooling of the refrigerant, which under most conditions should be able to overcome the additional heat infiltration causing a gradual reduction in the temperature of the space to be refrigerated.

Instead of using just a single by-pass 30 as shown, a plurality of by-passes may be employed which are controlled by valves operating at successively higher temperatures and each by-pass causing a further reduction in the pressure in evaporator 10. It will also be appreciated that the temperatures and pressures mentioned herein are merely illustrative of one form of setting and where different types of refrigerants are employed and different temperatures are desired different adjustments will also be required. Once the nature and operation of my device is understood, however, anyone skilled in the art will be able to adjust the thermostatically controlled switch 25, the pressure regulating valve 18, and the pressure operated switch 36 to produce the desired results.

It will be seen from the herein described and illustrated embodiment of my invention that I have provided an improved refrigerating apparatus, particularly control mechanism, whereby undesirable fluctuations in temperature in the refrigerated space can be eliminated and whereby a high degree of uniformity of temperature can be obtained. It will be understood that many modifications may be made in the illustrated and described embodiment of my invention such as combining the control mechanism with other types of refrigerating apparatus and by employing a plurality of by-passes as above described. Also instead of employing a suction tank 15 enlarged or extended piping may be employed.

I claim:

40 1. The combination with refrigerating apparatus having a compressor and an evaporator, of means having relatively large volumetric capacity as compared to the capacity of the evaporator and having connection with the outlet of the evaporator and with the intake of the compressor, thereby providing a relatively large space of reduced pressure communicating with the outlet of the evaporator, a pressure regulating valve in the connection between said means and the evaporator for regulating the minimum pressure in the evaporator, an automatically controlled valve for opening and closing said connection, a by-pass around said regulating valve, and an automatically operating control valve for the by-pass.

2. The combination with refrigerating apparatus having a compressor and an evaporator, of means having relatively large volumetric capacity as compared to the capacity of the evaporator and having connection with the outlet of the evaporator and with the intake of the compressor, thereby providing a relatively large space of reduced pressure communicating with the outlet of the evaporator, a pressure regulating valve in the connection between said means and the evaporator for regulating the minimum pressure in the evaporator, a control valve in said con-

nection having a thermostatic control for opening the valve at a predetermined temperature, a by-pass around the pressure regulating valve, and a control valve for the by-pass having a thermostatic control for opening the second-mentioned valve at a predetermined higher temperature. 5

3. The combination with refrigerating apparatus having a compressor and an evaporator, of means having relatively large volumetric capacity 10 as compared to the capacity of the evaporator and having communication with the intake of the compressor so as to provide a relatively large space of reduced pressure, a plurality of separate ducts each having communication at one end 15 with the outlet of the evaporator and at the other end with said means having a large volumetric capacity, a pressure regulating valve in one of said ducts for regulating the minimum pressure in the evaporator, and a control valve for each 20 of said ducts having thermostatically operated controls for opening the valves at predetermined temperatures, the valve in said duct which is provided with a pressure regulating valve being co-operable to open at a lower temperature than 25 the valve in the other duct.

4. The combination with refrigerating apparatus having a compressor and an evaporator, of a tank having connection with the intake of the compressor and with the outlet of the evaporator, 30 a pressure regulating valve in the connection between the evaporator and the tank for regulating the pressure in the evaporator, a control valve having a thermostatic control for opening the valve at a predetermined temperature, a by-pass 35 around the regulating valve, and a control valve for the by-pass having a thermostatic control for opening the second-mentioned valve at a predetermined higher temperature than the first-mentioned valve. 40

5. The combination with refrigerating apparatus having a compressor, condenser and evaporator, of a tank having a relatively large volumetric capacity as compared to the capacity of the evaporator and having connection with the intake of the compressor so as to provide a relatively large space of reduced pressure, a plurality of ducts having communication at one end with the outlet of the evaporator and at the other end with the said tank, a pressure regulating valve 50 in one of said ducts for regulating the pressure in the evaporator, and control valves for said ducts having thermostatic controls for opening the valve at predetermined temperatures, the control valve in the duct which is provided with a pressure regulating valve opening at a lower temperature than another of said valves. 55

6. In refrigerating apparatus, an evaporator, and means for reducing the pressure in the evaporator, said means including a pressure regulating valve for regulating the pressure in the evaporator at a predetermined level when a predetermined temperature is reached and means for rendering the pressure regulating valve ineffective when a higher predetermined temperature is 60 reached. 65
